UNITED STATES PATENT OFFICE.

HENRY UMPHREY, OF CARLETON PLACE, ONTARIO, CANADA, ASSIGNOR OF ONE-THIRD TO ELMER DONALD BENJAMIN ROBERTSON AND ONE-THIRD TO HARRY DAVID UMPHREY, OF ONTARIO, CANADA.

SUPPORT FOR WINDOW-BLIND ROLLERS, CURTAINS, VALANCES, AND THE LIKE.

1,346,354.

Specification of Letters Patent. Patented July 13, 1920.

Application filed March 12, 1920. Serial No. 365,182.

To all whom it may concern:

Be it known that I, HENRY UMPHREY, a subject of the King of Great Britain, a resident of the town of Carleton Place, Province of Ontario, Dominion of Canada, have 5 invented new and useful Improvements in Supports for Window-Blind Rollers, Curtains, Valances, and the like, of which the following is a specification.

10 This invention relates to improvements in supports for window blind rollers, curtains, valances, and the like, and the objects of the invention are to facilitate securing the support to a window frame without the use of 15 nails, and in such a manner that the support will be extremely strong and properly carry the several rods, roller curtains, and blinds, etc., with which it is provided.

Further objects are to permit of the support 20 being removed bodily from a window with the roller and rods in position, so that in this way the support can be taken down for the purpose of removing soiled blinds, curtains, etc., and replacing the same by 25 fresh ones, and in the case of fire it also permits of the blind and curtains being removed bodily thus facilitate saving the same.

Further objects still are to render the several rod supporting elements or members 30 detachable, so that only the requisite number of elements need be used and assembled for the purpose of carrying the blind and curtains, or the blind, curtain valance, tapestry, curtain and the like.

35 For a better understanding of my invention reference is made to the accompanying drawings in which an embodiment of the same is illustrated and in which:

Figure 1 is a vertical section through a 40 window frame showing my improved blind and curtain support in position.

Fig. 2 is a front elevation of the window frame showing my improved blind and curtain support thereon.

45 Fig. 3 is a perspective view of the assembled brackets which support the blind roller and the curtain rods, and showing the method of mounting the brackets on the supporting rod which is designed to be secured 50 to a window frame.

Fig. 4 is a plan view of one of the brack-

ets for securing the blind and curtain support to a window frame.

Fig. 5 is a side elevation of a bracket adapted to be secured to the supporting rod, 55 and designed to carry the blind roller.

Fig. 6 is a side elevation of a bracket adapted to coact with the bracket shown in Fig. 5 and support a curtain rod.

Fig. 7 is a side elevation of a bracket 60 adapted to carry a second curtain rod, and showing it in engagement with the bracket illustrated in Fig. 6.

Fig. 8 is a plan view of the bracket for securing the blind and curtain support to a 65 window frame, the method of securing being in this case an alternative to that shown in Fig. 4.

Fig. 9 is a side elevation of a bracket adapted to be utilized with the bracket shown 70 in Fig. 5, and to support a curtain and valance rod.

Like characters of reference refer to like parts in the several figures.

Referring to the drawings; A represents 75 a window frame of any usual description and B the improved blind and curtain support designed to be attached thereto.

This blind and curtain support comprises a supporting bar 10 which engages with the 80 front of the window frame A, and is provided with a pair of adjustable brackets 11 by means of which the bar 10 is secured in position.

Each bracket 11 consists of an eyelet 12 85 slidably engaging with the bar 10 and provided with a set screw 13 extending through the lower wall, and by means of which the bracket is adjustably secured in position on the bar.

Extending forwardly from the eyelet 12 is an arm 14 having a lateral pin projection 15 and on the opposite side an offset finger 16. The pin projection 15 is designed to be engaged with an orifice 17 in the side members of the window frame A, and when in this position the set screw 13 is tightened so that the bar 10 will be rigidly secured in position.

90 It should be particularly noted that the 100 bar 10 is preferably of rectangular section, so that a flat face will engage with the face

of the window frame A, and in this way twisting or canting of the bar 10 cannot take place.

Between the brackets 11 and the ends of the bar 10 I provide an adjustable bracket C comprising an eyelet 19 which slidably engages the bar 10, this eyelet having a set screw 20 through the lower wall. The eyelet 19 carries an upwardly extending arm 21, the inner edge 22 of which is straight while the outer edge 23 is curvilinear and at the upper end of the inner edge 22 a projection 24 is provided.

A projecting arm 25 is provided extending forwardly from the eyelet 19 and is designed to support a blind roller 26, and at the junction of the arm 25 and the curvilinear outer edge of the arm 21 a shoulder 18 is provided.

It will be understood that two brackets C are utilized, and while one of the brackets is provided with an orifice 27, to accommodate the pintle on the end of a blind roller 26, the other bracket will be provided with an angular slot 28 to accommodate the opposite end of the blind roller as seen in Fig. 3.

This equipment of a pair of brackets C, a pair of brackets 11 and the bar 10 can be utilized for the support of a blind roller.

To provide for a curtain rod a second bracket D is used having a rectangular end 31 provided with an offset member 32 which forms with the rectangular end 31, a guide adapted to engage with the upwardly extending arm 21 of the bracket C. The bracket D extends forwardly from the bracket C and terminates in a ring 33, adapted to receive and support a curtain or like rod.

At the lower edge of the rectangular portion 31 I provide a projection 34 having a cover plate 35 and the vertical edge or wall 36 of this projection is adapted to coact with the shoulder 18 on the curvilinear edge 23 of the arm 21 of the bracket C.

It should be particularly noted that when the bracket D is in alignment with the bracket C, then the projection 24 will overhang the upper edge of the rectangular portion 31 and prevent the bracket D from becoming displaced when the weight of curtain rods and curtains are brought to bear upon the said bracket.

The strain of supporting the curtain rod and curtains is also taken care of by the vertical wall or edge 36 of the projection 34 coming into intimate engagement with the shoulder 18 and prevents a bending moment tending to detach the bracket D from the arm 21 of the bracket C.

On the ring 33 a lateral projection 37 is provided and a pair of peripheral projections 38 and 39 are also provided.

In a case where another curtain rod is to

be used, that is to say, where two or three curtain rods are used, then the bracket E is provided having an orifice 43 designed to engage the end of a curtain rod, and this bracket E is provided with a hook shaped arm 44 which engages the lateral projection 37 of the bracket D.

This hook shaped arm 44 is provided adjacent to the orifice 43 with a rectangular recess 45 adapted to engage with the projection 39 on the bracket D, and the peripheral projection 38 engages with the outer face of the bracket 42.

This bracket E is also provided with a peripheral projection 46 which engages the opposite face of the bracket D to that engaged by the projection 38, so that the bracket E is held against downward and also against lateral displacement.

On the front end of the bracket E a hook 47 is provided which is adapted to engage with an extensible curtain rod 48, which curtain rod does not form part of the present invention and is well-known in the art.

Under some circumstances where a household is wholly provided with curtain rods such as illustrated at 48, then the brackets D and E may be dispensed with and a single bracket E will be mounted on the bracket C.

The bracket F is provided with a rectangular end 49 carrying a member 50 extending transversely thereacross and adapted to form a guide and gripping means which will engage with the vertical disposed arm 21 of the bracket C, and the projection 24 on the arm 21 will overhang the upper end of the rectangular portion 49 of the bracket F.

The bracket F is curvilinear in formation and extends forwardly from the bracket C and is provided on the lower edge with a projection 51, which engages with one of the lateral walls of the bracket C, and prevents lateral displacement of the bracket F.

On the front end of the bracket F a hook member 52 is formed with which the adjustable curtain rod 48 may be engaged. The construction of the several parts of the invention will be readily understood from the above description.

When a device of this nature is in use it is necessary to first determine how many curtains, valance, etc., are to be used, and it will be understood that in all cases a blind roller will be used.

The bar 10 is first taken and the bracket 11 located thereon, and if provision is made on the window frame A of a projecting portion 53 such as illustrated in Fig. 8, then the brackets 11 will be moved on the bar 10 to embrace the projection 53 whereupon the set screws 13 will be tightened.

If however as is generally the case there is no projecting portion such as 53, then a small tapered hole 17 may be formed

in the side members of the window frame A, and these holes will accommodate the pins 15 of the brackets 11 after which the set screws 13 are tightened. This secures the bar 10 in position.

The brackets C are placed on the bar 10 before the bar is actually positioned, but the final adjustment of the brackets only takes place after the bar 10 has been positioned.

10 The brackets C are spaced the desired amount to accommodate the blind rollers 26 whereupon the set screw 20 will be tightened.

15 The blind may be secured to a blind roller 26 and operated in the usual manner.

Having now determined how many curtain rods are to be used, the requisite brackets, D, E, and F are selected.

Supposing for instance that two curtains 20 are to be used then the bracket D is engaged with the bracket C as above described, the rectangular portion 31 and the transverse member 32 embracing the vertical arm 21 of the bracket C, and in this position the offset 25 projecting end 24 overhangs the upper edge of the rectangular portion 31 of the bracket D, while at the same time the vertical edge 36 of the projection 34 coacts with the shoulder 18 and thus prevents any tendency of 30 the bracket D being disengaged from the arm 21 of the bracket C.

The curtain rod may now be placed in the ring 33 and the necessary curtain hung.

35 The bracket E is now engaged with the bracket D, and the hook arm 44 is engaged with the lateral projection 37, and the projection 39 engaging with the recess 45 in the arm 44.

40 The projections 38 and 46 embrace the opposite side faces of the brackets E and D respectively and hold the bracket E against lateral displacement. The curtain rod can now be positioned in the orifice 48, and the necessary curtains hung.

45 While in describing this invention it has been stated that the bar 10 is positioned it would probably be better to explain that the whole of the blind and curtain support can be assembled before the bar 10 is positioned on the window A, and in fact the blind can be affixed to the blind roller 26 and the curtains fixed to their respective rods, and then the whole completed device may be placed on the window by adjusting the brackets 11 to engage with the frame of the window A and then tighten the set screws 13 on the bar 10.

If it is only necessary to use a single curtain rod of the expandable type 48, then the 60 bracket F is utilized instead of two brackets D and E. The rectangular end 49 is engaged with an upwardly extending arm 21 of the bracket C and the projection 24 overhangs the ends of the rectangular portion 49 of the bracket F and the projection 51 en-

gages with the lateral face of the bracket C, and prevents displacement of the bracket F, and the curtain rod 48 may now be positioned on the hook 52.

The several brackets 11, C, D, E or F are 70 always in alinement when assembled.

From the above description it will be seen that this invention provides a means for hanging blind rollers, curtains, etc, on windows without the use of any nails, and in 75 which the supports are in the form of removable brackets which may be assembled in the desired manner to suit the requirements of the user.

As many changes could be made in the 80 above construction and many widely different embodiments of my invention within the scope of the claims, constructed without departing from the spirit or scope thereof, it is intended that all matter contained in the 85 accompanying specification and drawings shall be interpreted as illustrative and not in a limiting sense.

What I claim as my invention is:

1. A support of the class described comprising a bar, a bracket adjustably mounted on the bar, and having lateral projections adapted to secure the bar to a window frame, a second bracket adjustably mounted on the bar, and designed to carry a roller, 95 and a plurality of brackets arranged in alinement with the second bracket and designed to carry curtain supporting means.

2. A support of the class described comprising a bar, a bracket adjustably mounted 100 on the bar, and having projecting means for securing the bar to a window frame, a second bracket adjustably mounted on the bar and designed to carry a roller, a plurality of brackets arranged in alinement with the 105 second bracket and supported thereby and designed to support curtain supporting means, and means for preventing lateral displacement of the last said bracket relatively to the second said bracket.

3. A support of the class described comprising a bar, a bracket adjustably mounted on the bar and having projections adapted to secure the bar to a window frame, a second bracket adjustably mounted on the bar 115 and designed to carry a blind roller, a third bracket supported by the second said bracket and provided with a lateral projection, a fourth bracket supported by the third bracket and provided with an arm engaging 120 the said projection, the third and fourth brackets being designed to carry curtain supporting means, and means for maintaining the second, third and fourth brackets in alinement and against lateral displacement. 125

4. A support of the class described comprising a bar, a bracket adjustably mounted on the bar and having means for securing the bar to a window frame, a second bracket adjustably mounted on the bar and having 130

4
a roller supporting member and an upwardly extending arm, the said arm having a projection on its rear edge and a shoulder on its front edge adjacent to the roller supporting member, and a third bracket having a guide means coacting with the vertically disposed arm and engaging with the projection and a shoulder coacting with the

said shoulder, the last said bracket being designed to support curtain supporting means. 10

In witness whereof I have hereunto set my hand in the presence of two witnesses.

HENRY UMPHREY.

Witnesses:

Wm. BAIRD,
LILY MOORE.
